LAY STRUCTURE FOR LOOMS

Carl J. Lindegren, Providence, R. I., assignor to
Crompton & Knowles Loom Works, Worcester,
Mass., a corporation of Massachusetts

Application October 19, 1931. Serial No. 569,573

9 Claims. (Cl. 139—184)

This invention relates to loom lays and it is the general object of the invention to provide simple means for aligning a part of the shuttle box construction with the reed.

In looms equipped with shifting shuttle boxes either for varying the color of the weft or for assisting in the replenishment of weft in a shuttle changing loom, the lay usually comprises in its construction a metallic so-called lay end which projects beyond the frame of the loom to guide both the picker stick and the shuttle boxes. The latter ordinarily include a gang of cells each of which will be defined by a top and bottom and also the shuttle binder. In certain constructions heretofore employed it has been customary to make the lay end with an integral surface which forms the back of the shuttle boxes so as to determine the flight of the shuttles as they are picked. With such a construction it is necessary to secure accurate alignment between the lay end, which is a relatively heavy and cumbersome casting, and the reed.

It is an important object of my present invention to provide an auxiliary plate which may be secured to the lay end and positioned without requiring movement of the lay end with respect to the lay, so as to present a correctly located surface to define the backs of the shuttle boxes.

By the use of the invention set forth herein the usual form of lay end is altered somewhat so that its forward face lies behind its usual position to make room for the auxiliary plate, and the lay end can be secured tightly to the lay wood or batten with assurance that when once located it will not have to be disturbed. The arrangement set forth herein renders it possible to provide a very rigid connection between the lay and the lay end, inasmuch as the movement required to adjust the back of the box is confined to a relatively small plate or the like carried by the lay end.

While the invention has been set forth more particularly in connection with a shuttle changer loom, such as shown for instance in patent to Chevrette No. 1,753,233 where replenishment is effected by shifting boxes, yet the invention is not limited to this arrangement, since it may be employed on the shifting box end of a fancy or multicolor loom.

It is a further and more specific object of my invention to provide a flat steel plate having a horizontal slot for the picker and suspended by means of screws which extend into the lay end and is determined as to position by other screws which extend through and are fastened to the

lay, but have abutting surfaces to act as variable stops. By having enough of the screws of the type just mentioned it is possible to vary the position of the plate as a whole relatively to the lay end and also to vary its angular position both in vertical and horizontal planes. In this connection it might be mentioned that some fixers consider the flighting of a shuttle is improved by having the back of the box disposed at a slight angle with respect to the reed, the angle being such that the outer end of the box is forward of the reed line. In this way the shuttle is given a slight rearward movement toward the center of the reed which has the effect of preventing the shuttle from flying out of the shed. The angle referred to can very easily be secured and varied by means of the auxiliary plate set forth hereinafter without requiring any loosening of the connection between the lay end and the lay wood.

The usual shuttle box is formed in part by a yieldable shuttle binder to push the shuttle against the back wall of the shuttle. It is a further object of the invention to combine with the binder a plate variable within comparatively small limits to define the box back against which the shuttle is pushed by the binder. The latter will yield to accommodate varying adjustments of the plate.

With these and other objects in view which will appear as the description proceeds, my invention resides in the combination and arrangement of parts.

In the accompanying drawing, wherein a convenient embodiment of my invention is set forth, Fig. 1 is a front elevation of a lay made according to my present invention.

Fig. 2 is a perspective view of a part of the lay end.

Figs. 3 and 4 are vertical sections on lines 3—3 and 4—4, respectively, of Fig. 1, and

Fig. 5 is a diagrammatic plan view of the lay showing the relation between the several parts of the lay.

Referring to the drawing, I have shown diagrammatically in Fig. 5 the general relation which the auxiliary plate sustains to the other parts of the lay. The lay wood 10 has secured thereto a metallic lay end 11 and the boxes 12 as shown are spaced slightly from the lay end to provide room for the auxiliary plate 13. The particular form of lay illustrated in Figs. 1, 3 and 4 is that which may be found in shuttle changer looms and has the usual reed 14 which may be secured to the lay in any approved manner and

projects upwardly to define a guide for the shuttle S. The binder 15 may be stationary with respect to the lay and held yieldingly in rear position by spring 16. The box structure 12 may 5 include top and bottom cells 17 and 18, respectively, the upper of which may be normally active to receive a shuttle during ordinary weaving.

The lay end may include a wall 19 which is slotted as at 20 to receive a slide picker 21 propelled by a picker stick 22. A pivoted top or cover 23 for the upper box is shown inasmuch as this is a part of the shuttle changer loom to which I have applied my invention.

It is to be understood that the boxes can be 15 raised from the position shown in the drawing by means of a lifter rod 24, so that the upper box can receive a shuttle from the magazine not shown and the lower box can receive the depleted shuttle to be expelled at some later point in the 20 cycle of the operation. Tongues 25 enter fixed grooved guides 26 to determine the plane of movement for the shuttle boxes. The guides 26 may be positioned relatively to the lay to give the 25 desired motion to the shuttle boxes, as suggested in Colgan Patent No. 1,786,703. The binder acts yieldingly to push the shuttle back against the plate 13.

Except for the plate 13 which has been mentioned the structure is substantially the same as 30 that already existing and of itself forms no part of my present invention. While the plate 13 has been described as part of a lay end found on shuttle changers, yet it can also be used on the ordinary fancy or drop box looms with equal effect. 35 In Figs. 3 and 4 it is to be understood that the dot and dash line 27 defines a so-called reed line along which the shuttle is to be moved. The race plate may extend along the dot and dash line 28 in these figures. These lines represent 40 planes which serve to guide the shuttle.

In carrying my invention into effect I provide means for positioning the plate 13 so that the same will assist in guiding the shuttle properly as the latter is picked. As shown herein I provide each of the corners of the plate with holding 45 screws 30 which are extended through the plate and threaded into the wall 19, as set forth more clearly in Fig. 3. Other screws 31 extend through wall 19 to serve as adjustable stops to position the plate 13, and nuts 32 may be used to lock the adjusted setting of these last named screws. Although I have shown but four pairs of holding 50 and positioning screws, yet it is to be understood that I may employ as many as are found necessary to position the plate, and they may be disposed both above and below the picker slot 33 extending longitudinally through the plate as suggested by Fig. 4.

When assembling, the lay end may be secured 60 to the lay sword 35 and lay wood in any approved manner, after which the plate 13 may be applied by means of the screws 30 to the wall 19 and the adjustable positioning screws 31 change until the vertical forward face 36 of the plate is 65 in correct alignment with the reed 14. The picker spindle 37 may be rendered adjustable to accommodate changing positions of the plate by a holder 38, such as shown in Patent No. 1,766,739. While this holder is desirable, yet it 70 is not necessary, inasmuch as the picker spindle can be fixed in predetermined position and the plate moved so as to position the rear wall of the shuttle box correctly with respect to such a position. During the rising and falling of the box 75 the plate will remain at rest and the horizontal

partitions which define the upper and lower boxes will slide past the plate, the latter being at all times in position to define the rear walls of the boxes.

From the foregoing it will be seen that I have 80 provided a lay employing in its construction an auxiliary plate to be adjusted with respect to the reed line and serving as the rear walls for shifting shuttle boxes. By this construction it is not necessary to position the lay end accurately 85 with respect to the reed line, so that a rigid and substantial connection can be made between the lay and the lay end which need not be disturbed, adjustments being made to afford the delicate 90 setting desirable on the part of the rear wall of the shuttle boxes by manipulating the holding and positioning screws to locate plate 13. Also, the binder, which need not be stationary as shown 95 herein, pushes the shuttle against the plate in any position the latter may assume.

Having thus described my invention it will be seen that changes and modifications may be made 100 therein by those skilled in the art without departing from the spirit and scope of the invention and I do not wish to be limited to the details herein disclosed, but what I claim is:

1. In a loom lay, a batten, a lay end rigid with respect thereto, shifting shuttle boxes, and a guide 105 between the lay end and boxes capable of being held in any one of several positions relatively to the lay end to vary the alignment of the shuttles with respect to the batten, said guide forming part of the shuttle boxes during shifting thereof.

2. In a loom lay, a batten having a reed, a lay 110 end rigid with respect to the batten, shifting shuttle boxes, a shuttle guide between the lay end and shuttle boxes forming a wall of the latter, and means to secure the guide to the lay end in any one of a plurality of positions to vary the alignment of the shuttles in the boxes with respect to the reed.

3. In a loom lay a batten having a reed, a lay 115 end rigid with respect to the batten, shifting shuttle boxes, a shuttle guide between the lay end and shuttle boxes forming a wall of the latter, a 120 binder to force a shuttle in one of the boxes against the guide, and means to secure the guide to the lay end in any one of a plurality of positions to vary the alignment of the shuttles in the boxes with respect to the reed.

4. In a loom lay, a batten having a reed, a lay 125 end rigid with respect to the batten, shifting shuttle boxes, a binder forming part of the boxes, a plate secured to the lay end and located on that side of the boxes opposite the binder, and means 130 to give the plate any one of a plurality of settings relatively to the lay end to vary the position of the shuttles in the boxes relatively to the reed, the binder movable to accommodate varying positions of the plate.

5. In a loom lay, a batten having a reed, a lay 135 end rigid with respect to the batten, shifting shuttle boxes, a plate on one side of the boxes forming one side thereof, stop elements interposed between the lay end and plate to give the latter a plurality of positions relatively to the lay end, and means to hold the plate in any of said positions with respect to the lay end to align the shuttles in the boxes with the reed.

6. In a loom lay, shifting shuttle boxes, a batten, 140 two attached members supported by the batten, one of said members secured rigidly to the batten, the other member forming part of the boxes and serving to guide a shuttle, positioning elements carried by one member to engage the other mem- 145

ber to give said members a plurality of different relative positions, and holding elements connecting the members together.

7. In a loom lay operating with a picker, shifting shuttle boxes, a lay end fixed to the lay, a plate secured to the lay end and having a slot therein for the picker and forming part of the boxes, and holding and positioning means to locate the plate rigidly in any one of a plurality of positions on the lay end to vary the position of the shuttles in the boxes relatively to the lay.

8. In a loom lay having a reed thereon, a lay end fixed with respect to the lay, a shuttle box movable vertically with respect to the lay end, a 15 guide plate on the lay end forming the rear wall

for the shuttle box, retaining screws passing through the plate into the lay end to retain the plate in any one of a plurality of positions, and stop screws held in the lay end and capable of being moved to contact with the plate, said screws acting to hold the plate in alignment with the reed according to the position which the plate assumes.

9. In a loom, a lay, a reed to guide the shuttle, a lay end forming part of the lay, a shuttle box movable vertically, and means on the lay end forming a shuttle compartment with the shuttle box and movable to keep the shuttle aligned with the reed.
